UNITED STATES PATENT OFFICE

126,485

DESIGN FOR A RECEPTACLE FOR CIGARETTES AND OTHER ARTICLES

Alfred F. Reilly, North Attleboro, Mass.

Application January 29, 1941, Serial No. 98,514

Term of patent 7 years

To all whom it may concern:

Be it known that I, Alfred F. Reilly, a citizen of the United States, residing at North Attleboro, county of Bristol and State of Massachusetts, have invented a new, original, and ornamental Design for a Receptacle for Cigarettes and Other Articles, of which the following is a specification, reference being had to the accompanying drawing forming a part thereof.

In the accompanying drawing,

Fig. 1 is a top plan view of a receptacle for cigarettes and other articles showing my new design.

Fig. 2 is a front elevational view of the same.

Fig. 3 is an end elevational view of the same.

The side of the article illustrated not shown is plain.

The dominant feature of the invention resides in the raised ornamentation on the top of the receptacle.

I claim:

The ornamental design for a receptacle for cigarettes and other articles, substantially as shown and described.

ALFRED F. REILLY.
